WALLACE I. STIMPSON, OF HOPEDALE, MASSACHUSETTS, ASSIGNEE TO DRAPER CORPORATION, OF HOPEDALE, MASSACHUSETTS, A CORPORATION OF MAINE

BOBBIN AND BOBBIN CLUTCHING SPINDLE

Application filed February 23, 1932. Serial No. 594,843.

This invention relates to that type of spinning apparatus in which a rotatable spindle having a plurality of centrifugally-acting clutch segments is employed. In this type of apparatus the rotation of the bobbin with the spindle is secured by the radial pressure of the clutch segments against the wall of the bore in the butt of the bobbin. As commonly constructed, there is nothing to prevent the bobbin from rising vertically on the spindle except the friction between the clutch segments and the said wall. It frequently happens that the top of the bobbin becomes worn enough to be slightly loose on the spindle, or the bobbin becomes unbalanced dynamically. In either event, the stresses set up at the extremely high speeds at which the bobbins and spindles are rotated are sufficient to cause the top of the spindle to be pulled out of line and to rotate bodily in a more or less circular path. When this happens, quite an appreciable component of the centrifugal force set up tends to lift the bobbin vertically off the spindle, and the aforementioned friction is insufficient to keep the bobbin down in place. Of course, if the bobbin rises, even slightly, during the spinning operation a uniform traverse is not produced, and the particular package of yarn is rendered defective.

Accordingly, the object of the present invention is to provide a construction in which the bobbin will be firmly held against rising on the spindle.

In my prior Patent 758,715, granted May 3, 1904, I disclosed a construction intended to prevent bobbins from rising on the spindles, by merely making the bore in the butt of the bobbin tapered. However, such construction was not satisfactory and it has never been used, partly because the tapered bore cannot be satisfactorily produced commercially and partly because the bare wood was rapidly mutilated by the metal clutch segments. Also a metal bushing to withstand the stresses set up by the steel rings cannot be satisfactorily inserted in the tapered bore.

I accomplish the desired result in the present instance by a construction hereinafter de-

scribed, and shown on the accompanying drawing, in which:

Fig. 1 is an elevation of a centrifugal clutch spindle with a bobbin placed thereon, the bobbin being cross-sectioned to more 55 clearly show my invention;

Fig. 2 is an enlarged sectional elevation of the butt of the bobbin shown in Fig. 1;

Fig. 3 is a view similar to Fig. 1 but showing a different form of my invention, and 60

Fig. 4 is an enlarged sectional elevation of the butt of the bobbin shown in Fig. 3.

The spindle illustrated comprises the usual blade 1 with the whirl 2 rigidly secured thereon, and a centrifugal bobbin clutch 3 65 which includes a slotted sleeve 4 providing guides for pivotally mounted clutch segments 5 the upper, or exposed, ends of which incline upwardly and outwardly away from the axis of the spindle. When the spindle 70 is rotated the upper ends of the clutch segments tend to fly out away from the blade and this centrifugal action is utilized to drive the bobbin.

This spindle may be, as herein shown, identical with that disclosed in my prior Patent No. 1,796,770, granted March 17, 1931, and, accordingly, need not be further illustrated or described.

The bobbin illustrated in Figs. 1 and 2 80 includes a barrel portion 6 and a butt portion 7, the barrel portion being bored longitudinally as at 8 and provided with a metal bushing 9 for cooperation with the spindle 85 blade.

The butt 7 of the bobbin is provided with an enlarged bore 10 the lower portion of which houses the centrifugal clutch. Within the bore 10 is positioned a metal bushing 90 11 which, as shown, extends from a point well below the gripping portions of the clutch segments to a point thereabove, the bushing thereby serving the dual purpose of protecting the wood of the bobbin from the mutilating action of the clutch segments and reinforcing the bobbin against the stresses imparted by the steel rings 12 which fit very tightly on the butt of the bobbin. The bushing is rigidly secured in the bore 10 in any 100

suitable manner, as by being spurred to the wood.

The bushing 11 is slightly larger in diameter, inside, than those usually employed for cooperation with a given size of bobbin clutch, and is provided, approximately midway of its ends, with an inwardly projecting, circumferential ledge. The inner edge of this ledge is of slightly less diameter than the internal diameter of the bushings used heretofore, and bears against the clutch segments well below their tops. The exact manner of procuring this ledge is not of primary importance, although I have shown two methods which I believe to be the best.

In Figs. 1 and 2 the ledge 13 is constituted by the upper edge of an inwardly projecting annular flange formed in the bushing 11 before it is inserted in the bore 10.

In Figs. 3 and 4, the barrel 6', butt 7', bore 8', bushing 9', bore 10' and rings 12' are identical with the corresponding parts in Figs. 1 and 2. The bushing 11' is likewise identical with bushing 11 except that in bushing 11' ledge 13' is constituted by the upper edge of a shorter bushing 14 inserted within and fixed to the bushing 11' in any suitable manner as by being spurred thereto. The bushing 14 is approximately half the length of the bushing 11 and ledge 13' is, accordingly, positioned approximately midway of the ends of the longer bushing and well below the tops of the clutch segments.

The diameter of the inner edge of ledge 13, 13' is such that it will bear firmly against the clutch segments when the bobbin is down on the spindle, and the inclined faces of the clutch segments will, when the spindle is rotated rapidly, very effectively hold the bobbin in position.

The diameter of the bushing 11 or 11', above the ledge, should be such that the clutch segments contact the inner wall of the bushing with about the same force as they exert against the ledge, thereby providing for each clutch segment two places of driving contact. This greatly enhances the frictional driving grip exerted on the bobbin without detracting from the efficacy of the ledge in preventing the bobbin from rising on the spindle.

The aforementioned results may, of course, be attained in other ways without departing from the spirit of the invention as defined in the appended claims, it being particularly noted that while I have shown the ledge as being continuous I do not wish to limit myself to such a construction.

Having fully disclosed the two preferred embodiments of my invention I claim:

1. The combination of a rotatable spindle having a plurality of clutch segments which incline outwardly and upwardly away from the axis of the spindle, with a bobbin having a metal bushing in a bore in the butt there-

of, serving to house the clutch segments, said bushing being provided with an inwardly projecting locking ledge, of less diameter than the remainder of the bushing, the ledge engaging the inclined clutch segments below the tops thereof and locking the bobbin against rising on the spindle.

2. The combination of a rotatable spindle having a plurality of clutch segments which incline outwardly and upwardly away from the axis of the spindle, with a bobbin having a metal bushing in a bore in the butt thereof, serving to house the clutch segments, said bushing being provided intermediate its ends, with a continuous, inwardly projecting, locking ledge of less diameter than the remainder of the bushing, the ledge engaging the inclined clutch segments below the tops thereof and locking the bobbin against rising on the spindle.

3. The combination of a rotatable spindle having a plurality of clutch segments which incline outwardly and upwardly away from the axis of the spindle, with a bobbin having a metal bushing in a bore in the butt thereof, serving to house the clutch segments, said bushing being provided, intermediate its ends, with an inwardly projecting annular flange, of less diameter than the remainder of the bushing, the upper edge of the flange engaging the inclined clutch segments below the tops thereof and constituting a locking member for locking the bobbin against rising on the spindle.

4. The combination of a rotatable spindle having a plurality of clutch segments which incline outwardly and upwardly away from the axis of the spindle, with a bobbin having a metal bushing in a bore in the butt thereof, said bushing extending from a point below the clutch segments to a point thereabove, and a shorter metal bushing positioned within and secured to the first said bushing, the top edge of the shorter bushing constituting a circumferential locking ledge engaging the inclined clutch segments below the tops thereof and locking the bobbin from rising on the spindle.

5. The combination of a rotatable spindle having a plurality of clutch segments the exposed portions of which incline outwardly and upwardly away from the axis of the spindle, with a bobbin having a cylindrical metal bushing secured in a bore in the butt thereof, the top edge of said bushing being continuous and also being smaller in diameter than the diameter of a circle defined by the tops of the exposed portions of the clutch segments, the said top edge of the bushing engaging beneath the outwardly inclined clutch segments and locking the bobbin down on the spindle.

6. A bobbin for use with rotatable spindles having locking members, said bobbin having a cylindrical bore in the butt thereof, and a

metal bushing secured in the said bore, the said bushing being substantially cylindrical and provided, intermediate its ends, with an inwardly projecting annular flange the upper edge of which flange constitutes a locking ledge for engaging the locking members of the spindle to hold the bobbin down on the spindle.

7. A bobbin for use with rotatable spindles having locking members, said bobbin having a bore in the butt thereof, a metal bushing secured in the said bore, and a shorter metal bushing positioned within and secured to the first said bushing, the shorter bushing terminating a substantial distance below the top of the first bushing, and the top edge of the said shorter bushing constituting a locking ledge for engaging the locking members of the spindle to hold the bobbin down on the spindle.
